UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,771, dated October 31, 1899.

Application filed October 5, 1899. Serial No. 732,727. Term of patent 14 years.

To all whom it may concern:

Be it known that I, JEREMIAH A. SCRIVEN, a citizen of the United States, residing in the borough of Manhattan, city, county, and 5 State of New York, (post-office address No. 18 East Fifteenth street,) have invented and produced a new and original Design for Bifurcated Nether Garments, of which the following is a specification.

- o The characteristic feature of my design consists in an insertion or panel let into the center of the seat portion of the garment and bordered on each side by elongated panels or insertions extending from substantially the 10 upper end of the garment and substantially throughout the tubular members thereof.

In the accompanying drawing the figure represents a rear view of a bifurcated nether garment embodying my design.

- o A in the drawing designates the body por-

tion of a bifurcated nether garment, from which project tubular members B. Let into the central portion of the seat of the garment is an insertion or panel C, which has ribs or wales *a* extending therethrough transverse to the length of the garment. This panel C is bordered by elongated insertions or panels D, which extend from substantially the upper end of the garment through the body portion thereof and substantially throughout the tubular members. The ribs or wales *b* of each of the insertions D are shown extending longitudinally throughout the length thereof. 25 30

What I claim is—

The design for a bifurcated nether garment, 35 substantially as herein shown and described.

JEREMIAH A. SCRIVEN.
